[57] **CLAIM**

The ornamental design for a guard for preventing fish from swallowing hook, as shown and described.

DESCRIPTION

FIG. 1 is a perspective view of a guard for preventing fish from swallowing hook showing my new design in condition of use with a fishing line and hook shown in broken lines; FIG. 2 is a top plan view thereof, it being understood that the bottom plan view is a mirror image thereof; FIG. 3 is a side elevational view thereof, all other side elevational views being the same except for the placement of the grooves; and,

FIG. 4 is a side view thereof in condition of use, with a fishing line and fish shown in broken lines.

The broken line showing of environmental structure is for illustrative purposes only and forms no part of the claimed design.
